PORTABLE HOT WATER RADIATOR

Original Filed Aug. 11, 1923

UNITED STATES PATENT OFFICE.

FRED C. BROWN, OF SEATTLE, WASHINGTON.

PORTABLE HOT-WATER RADIATOR.

Application filed August 11, 1923, Serial No. 656,928. Renewed February 4, 1925.

To all whom it may concern:

Be it known that I, FRED C. BROWN, a citizen of the United States, residing at Seattle, in the county of King and State of Washington, have invented a new and Improved Portable Hot-Water Radiator, of which the following is a specification.

The invention resides in the provision of a portable hot-water radiator adapted for use with electricity as the heating energy.

The invention has for its object to provide a radiator of the type stated which is of a simple and economical nature and which is so constructed as to be readily movable from one room to another as may be desired and connectible to any standard electric service plug, and in which provision is made for quickly and effectively heating the water and for causing the circulation of the same while being heated and wherein is included a thermostatic control for automatically turning on or off the electrical energy at certain temperatures of the water.

With the above and other objects in view, the invention further resides in those novel details of construction, combination of and arrangement of parts, all of which will be first fully described, then be particularly pointed out in the appended claims, reference being had to the accompanying drawing in which:—

Figure 1 is a central vertical longitudinal section of my invention.

Figure 2 is a view, similar to Figure 1, in which a slightly modified arrangement of the invention is shown.

In the drawing, 1 indicates the tubes of the radiator, which includes the usual upper cross passages 2 and the lower cross passages 3. The radiator body is also provided with suitable legs 4 equipped with casters 5 to permit the ready moving of the radiator from place to place about a room.

A suitable filling vent 6 is provided through which the water to be heated and circulated through the radiator may be filled thereinto.

At a suitable point in the lower part of the radiator body an outlet 7 is provided

leading into a circulating pipe 8 which, it 50 will be observed from Figure 1, is positioned upon an incline to aid in the circulation of the water of lower temperature downwardly therethrough.

The discharge end 9 of the circulating pipe 8 discharges the water circulated therethrough upwardly into the water heating chamber 10, in which is suitably mounted, in position for causing the circulated water to pass upwardly therethrough and in contact therewith, an electric resistance heating unit 11.

A vertical circulating pipe 12 projects upwardly through the top of the heating chamber 10, paralleling the adjacent radiator tube 1 and discharging into the upper portion of the radiator body as at 13.

From the foregoing description, it will be observed that the water filled into the portable radiator through the removable plug 6 will, when it is suitably heated by the heating unit 11, be caused to circulate in the usual manner through the various tubes 1, the upper cross passages 2 thereof and the lower cross passages 3 thereof and through the circulating pipe 8, heating chamber 10 and the vertical circulating pipe 12. The water of lower temperature continuously passes out through the outlet 7 and the circulating pipe 8 to be heated during its upward passage through the discharge 9 into the vertical circulating pipe 12 and therethrough, in its heated condition, into the top of the radiator body through the discharge 13. By reason of positioning the circulating pipe 8 on a downward incline a more effective outflow of the water of lowest temperature is effected, and by reason of positioning the heating unit 11 within the upward passage of the water as it leaves the discharge 9, the said heating unit cooperates with the natural tendency of heated water to rise to the top, and, by reason of such position, more effectively facilitates circulation of the water through the various passages of the radiator body.

To provide for proper cutting in and out of the electric energy for heating the ele-

ment 11, and for providing for such cutting on or off at predetermined temperatures of the water within the radiator, I provide any suitable type of thermostatic control 14 which is adaptable for automatically cutting off the electric energy at a predetermined maximum temperature and for automatically turning on the electric energy at a predetermined low temperature and which 10 has provision by which the current can be cut off entirely when the radiator is not in use. 15 designates the control handle of the thermostatic control device and which is adapted to be hand operated for setting the thermostatic control, as above described.

16 designates the electric wire connection whereby the radiator may be connected up with any standard wall plug. When the wire 16 is suitably connected with a standard wall plug, current is adapted to flow through the same to the thermostatic control 14 and out from the thermostatic control through a conduit 17 to the heating unit 11.

As the water becomes hot passing through 25 the heating chamber 10, it rises to the top causing the cold water at the bottom of the radiator to enter at 7 and circulate through the pipe 8 which enters the heating chamber 10 below the heating element 11, as hereinbefore described. The circulation of the water is indicated by arrows.

The cold water being drawn from the bottom, the radiator soon becomes hot through the thermal action of the hot water circulating 35 through the sections. When the water in all of the sections reaches the maximum temperature for which the thermostatic control 14 is set, the electricity is automatically shut off. As the water radiates its stored 40 up heat, the electricity is not used, making a great saving in the maintenance of the radiator. When the temperature of the water again falls below the low temperature point for which the thermostatic control is set, it 45 automatically turns on the electric current to again bring the circulating water to its maximum temperature.

It will be observed that the thermostatic control 14 is positioned in that tube farthest 50 remote from the end of the radiator at which the heating chamber 10 is positioned, thus the said thermostatic control will not be brought into action until the water in all sections of the radiator has been brought up to the maximum temperature.

It will be readily apparent that by positioning the heating chamber 10 at one end of the radiator body, and the discharge 7 at the opposite end of the radiator body, a 60 thorough circulation of the water through all sections of the radiator is effected.

A suitable height indicating gauge 18 may be mounted upon the radiator for indicating the height of the water therein.

65 In the form of my invention shown in

Figure 1 the heating chamber 10 is positioned outside of the radiator body proper and delivers the hot water to the top of the radiator through the pipe 12 and its discharge 13.

In Figure 2 is shown a slightly modified adaptation of the invention in which all of the radiator tubes 1 communicate at their bottoms with a common cross water passage 19 and the heating chamber 10 is projected 70 directly into the cross passage 19, at one end thereof, and is provided with an open top or discharge 20 through which the water passing therethrough and heated thereby may, through its thermal action, rise directly to the top of the radiator, thereby causing the water to circulate through the radiator and through the circulating pipe 8 which, in this instance, projects upwardly 85 into the cross water passage 19 at that end 85 of the radiator remote from the end in which the heating chamber 10 is mounted.

From the foregoing description, taken in connection with the accompanying drawing, 90 it is thought the complete construction, operation and advantages of my invention will be readily understood by those skilled in the art.

What I claim is:

1. A portable hot water radiator comprising water chambers, said radiator having means for permitting water circulation through the chambers, an electric resistance heating element, a heating element chamber in which said element is located, means for conveying water from the bottom of the radiator into the bottom of said heating element chamber and delivering the heated water from the top of said heating element chamber into the radiator chamber, substantially as shown and described. 95

2. A portable hot water radiator comprising a plurality of water chambers in communication with each other at the top and bottom to permit water circulation, means for causing the water to circulate through the water chambers, said means comprising a heating chamber, an electric resistance heating element located in said heating chamber, means effecting communication between the upper end of said heating chamber and the interior of the water chambers whereby the hot water from the heating chamber may flow upwardly into the water chambers, and a duct, one end of which communicates with the bottom of the radiator proper and the other end delivers into the bottom of the heating chamber. 100

3. A portable hot water radiator comprising a plurality of water chambers in communication with each other at the top and bottom to permit water circulation, means for causing the water to circulate through the water chambers, said means comprising a heating chamber, an electric resistance 115
